GARMENT SUPPORT

Gus Richter, New York, N. Y.

Application February 3, 1936, Serial No. 62,053

8 Claims. (Cl. 312—178)

This invention relates to improvements in garment supports, and more particularly to detachable fixtures.

Among the principal objects which the present invention has in view are: To provide improved means adapted to be easily attached to or detached from wardrobe suitcases, wardrobe trunks, salesmen's sample cases, steamer trunks, steamer wardrobe closets, building closets and so forth for the reception of garments; to be enabled to utilize such means to occupy minimum space and easily handled; to be enabled to remove the improved garment support with a plurality of garments thereon without disturbing the garments; to provide a garment support with means for receiving and supporting a plurality of garments without interfering with the operation of the support; to be enabled to swing the garment support means to any angle; to be enabled to slide the garment support outwardly and to swing the support means to a fully extended position; to provide means whereby the garment support may ride in swinging condition; to secure simplicity of construction and operation; and to obtain other advantages and results as may be brought out in the following description.

Drawings

Figure 1 is a front elevation of a wardrobe suitcase in open position and embodying my invention;

Figure 2 is a sectional view showing the features of the invention in closed condition and illustrating the sliding member in dotted lines 35 when extending outwardly therefrom, the section being taken on line 2—2 of Figure 1;

Figure 3 is a similar view and showing all movable parts in fully extended condition, the section being taken on line 3—3 of Figure 1;

Figure 4 is a bottom plan of the garment support;

Figures 5 and 6 are vertical sectional views of one part of the sliding member and the swinging member in several positions, shown as taken on line 5—5 of Figure 3; and

Figure 7 is a detail section shown as taken on line 7—7 of Figure 4.

Description

As will be seen in the drawings, the invention is more especially directed to a detachable support 10 adapted to be removably attached to wardrobe suitcase 11 as illustrated in Figures 1, 2 and 3 of the drawings. While I have shown my improved support attached to a suitcase, I

do not wish to be limited to the specific showing, and it is to be noted that the said support 10 may easily be attached to wardrobe trunks, sample cases, steamer trunks, wardrobe closets and numerous other convenient places wherein a plurality of garments, such as dresses may conveniently be carried and/or stored. Also, the support may easily be removed from a carrying device without disturbing or crushing the garments thereon, and then conveniently suspended from a hook or the like, in which condition the garments may then be inspected or removed from the support without disturbing the remaining garments.

The garment support may be of any suitable construction and/or configuration, and as illustrated preferably comprises a substantially V-shaped frame member 12 connected at its smaller end by a cross-piece 13. The wider part or outer end of the V is preferably connected as by an arcuate cross-rod 14, the purpose of which will be hereinafter more fully described. As shown in Figure 4, the elongated side pieces or arms comprising the V-shaped frame 12 are provided with a plurality of open-end bayonet slots 14'. By virtue of the said slots 14' the frame 12 may conveniently be attached to the wardrobe suitcase 11 as by wing nuts 15 screwed to a like number of screw bolts 16 passing through the top of the suitcase as will be seen in Figures 1 and 2. If desired, and in order to remove the frame and support from the suitcase or other place, the wing nuts 15 may be loosened after which the device may easily be removed by the simple expedient of moving it slightly toward the open end of the suitcase until the threaded ends of the bolts 16 are in registration with the open ends of the slots 14 and then moving it away from the threaded ends of the bolts.

Pivoted next one end of itself to the middle of cross-piece 13, as by a bolt 17, is a forwardly projecting rail 18 shown as preferably of an elongated hollow structure substantially square in cross section. Said rail at its pivoted end is shown as having its pivoted end filled in and this filled in end provided with a horizontal slot 19 cut inwardly from the end and fitting the cross-piece 13. Ample depth or clearance is provided for the slot to permit swinging of the rail 18 from side to side. A sliding member 20 is carried by said rail and held therein as by inwardly extending flanges 21 at the underside thereof, thereby providing a longitudinal opening or slot 22 at the underside of the rail, and extending from adjacent the inside or pivoted end, 55

and outwardly towards and adjacent the outer end or the end which normally is at the open end of the suitcase or the like. Said sliding member 20 has a hook 23 depending from next the 5 rear end of said member through said slot 22 and acts as a stop when the sliding member is fully extended as seen in Figure 3, by engaging the forward end of the slot.

The outer end of said sliding member 20 provides a depending portion 24 which is preferably 10 an integral part of the said sliding member. At the lower end of said depending portion 24 is pivotally mounted thereto a horizontally swinging rod 25 substantially the length of the sliding 15 member 20. Said swinging rod 25 is held to the depending portion 24 by a bolt 26 passing upwardly through the bottom of the substantially square end of the horizontal rod 25 and secured to the depending portion as by being screwed 20 thereto. In order that the rod may have freedom of movement and be permitted to swing freely when in use, there is provided a clearance 27 extending the thickness of the square end of the rod through which the bolt 26 passes.

25 The arcuate portion of the cross-rod 14 lies in a horizontal plane as will be seen from the several figures of the drawings. The outer extremities turn upwardly normal to that plane and are attached at their upper ends, by welding 30 or otherwise, to the outer ends of the V-shaped arms or members 12, 12. It is preferable that the plane of the arcuate portion of the cross-rod be coincident with the plane in which the underside of the rail 18 rests and swings, and in actual 35 practice said arcuate portion supports the outer end of said rail 18. It further is to be noted that the said arcuate cross-rod also may be conveniently used as a stop for the inward or retractive movement of the sliding member 20 and 40 for such purpose the said depending portion 24 is notched at its rear face as at 28.

In service, as when the case 11 is being transported, slide 29 is slid to its innermost position as 45 shown in Figure 2, and rod 25 is at that time 50 swung around to underlie the rail and slide and receive support from hook 23. The clearance 27 at the pivoting enables the said rod to be swung into the hook, and when the case is opened and the sliding member 20 is drawn forward and out 55 of the case, then that clearance again enables the rod 25 to be unhooked and swung around to extended position as shown in Figure 3, to project in the same general direction as the sliding member 20. When the rod is in this extended 60 position, garments on suitable hangers (not shown) may be placed in suspended position on the rod, after which the rod is swung back to normal or closed position and locked in place in the hook 23. The sliding member 20 then is slid 65 back as far as it will go, and the cover 29 of the case 11 closed and the sliding member thereby locked in place.

If desired to exhibit garments and without removing them from the swinging rod 25, the sliding member 20 may be slid out, in which condition the garments will be entirely out of the suitcase and free to be sorted or inspected. For convenience in use, and for purposes of clearing obstacles outside the suitcase or the like, the rail 70 18 with sliding member 20, and the swinging rod 25 may easily be swung to any desired angle as shown in Figure 4. In this connection, it is to be observed the sliding member 20 may or may not be slid outwardly and the swinging rod with garments hanging therefrom can be swung to any 75

desired position and the rail 18 with its housed sliding member swung by virtue of the pivoted end along the arcuate cross-rod 14 to positions shown in broken lines. If desired to hang all the 5 contents in a closet, the V-shaped frame member may be removed from the case and the entire hanger, with garments still suspended therefrom hung upon a closet hook until ready to return them to the case.

I claim:

1. A garment support as characterized comprising a V-shaped supporting member having means for attaching to a suitcase and the like, said means comprising a plurality of open-end bayonet slots adapted to receive bolts therethrough, means for holding the supporting member in the suitcase and the like, a rail pivotally mounted to the V-shaped member at one part thereof, and a depending arcuate cross-rod connecting said V-shaped member at another part thereof, said rail being supported by and free to swing across said arcuate cross-rod, and a sliding member telescoping into said rail substantially the length of the rail and adapted to support garments thereon when in extended 20 condition.

2. A garment support as characterized comprising a V-shaped supporting member having means for attaching to a suitcase and the like, a rail pivoted at one end of said supporting member, a cross-rod underlying said rail near its other end upon which said rail may be swung, and a sliding member telescoping into said rail, said sliding member at its telescoped end providing downwardly projecting means adapted to engage the cross-rod whereby the sliding member is prevented from becoming displaced from the rail when slid outwardly therefrom, and said sliding member when in extended condition is adapted to receive hangers and the like.

3. A garment support as characterized comprising a V-shaped supporting member having means for attaching to a suitcase and the like, a rail pivoted at one end of said supporting member, a cross-rod underlying said rail near its other end upon which said rail may be swung, a sliding member telescoping into said rail, and a rod at the outer end of said sliding member and depending therefrom for receiving hangers and the like.

4. A garment support as characterized comprising a rail pivoted at one end, a cross-rod underlying said rail near its other end upon which said rail may be swung, a sliding member extensible from said rail, a rod pivoted to the outer end of said sliding member for receiving hangers and the like, and a hook also carried by the sliding member near its inner end for affording another support for said rod.

5. A garment support as characterized comprising a rail pivoted at one end, an arcuate cross-rod underlying said rail near its other end upon which said rail may be swung, a sliding member extensible from said rail, said sliding member providing a depending portion adapted 65 to be on the outside of the cross-rod, and a rod pivoted to the underside of said depending portion for receiving hangers and the like and adapted to swing to any position.

6. A garment support as characterized comprising a rail pivoted at one end, an arcuate cross-rod underlying said rail near its other end upon which said rail may be swung, a sliding member extensible from said rail, said sliding member providing a depending portion adapted to be on the 75

outside of the cross-rod, and a rod pivoted to the underside of said depending portion for receiving hangers and the like, and a hook also carried by the sliding member near its inner end 5 for affording another support for said rod.

7. A garment support as characterized comprising a V-shaped supporting member having means for attaching to a suitcase and the like, a rail pivoted at one end of said supporting member, an arcuate cross-rod attached to the supporting member and underlying said rail near its other end upon which said rail may be swung, a sliding member extensible from said rail, said sliding member providing a depending portion 10 adapted to be on the outside of the cross-rod, a rod pivoted to the underside of said depending portion for receiving hangers and the like, a hook carried by the sliding member near its inner end for affording another support for said rod, and 15 said rail having a slot on the underside thereof through which a portion of the hook extends.

8. A garment support as characterized comprising a V-shaped supporting member having means for attaching to a suitcase and the like, a rail pivoted at one end of said supporting member, an arcuate cross-rod attached to the supporting member and underlying said rail near its other end upon which said rail may be swung, said arcuate cross-rod having uprights at its outer ends secured to the outer ends of said V-shaped member and thereby supported thereat, 10 a sliding member extensible from said rail, said sliding member providing a depending portion on the outside of the cross-rod, a rod pivoted to the underside of said depending portion for receiving hangers and the like, a hook carried by the 15 sliding member near its inner end for affording another support for said rod, and said rail having a slot on the underside thereof through which a portion of the hook extends.
